PROCESS AND APPARATUS FOR CLEANING
COALS AND OTHER MATERIALS

Klaas F. Tromp, Kerkrade, Netherlands

Application April 16, 1936, Serial No. 74,650
In Germany May 23, 1935

10 Claims. (Cl. 209—173)

This invention relates to processes and to apparatus for separating solid materials having different specific gravities by means of a suspension, especially, although not exclusively, for 5 cleaning or dressing coals so as to separate the pure coal from the accompanying impurities such as slates and pyrites.

Hereinafter the word "water" will be used to mean any liquid suitable for the purpose, and the 10 word "sand" will be used to mean any comminuted insoluble material heavier than the liquid and adapted to be used as the solid constituent of the suspension.

We are aware that for the wet cleaning of 15 coals by means of a suspension several processes have already been suggested. In the Chance process, a mixture of sea sand or the like and water is used for causing the coal to float and the slate to sink therein. This fluidic mixture 20 is mechanically agitated and, in addition, a rising current of water is introduced near the bottom of the tank, said current being so strong that, while the slate is allowed to sink, the sand is kept in suspension. It follows that it should be en- 25 deavoured to keep the density of the suspension approximately constant and uniform throughout practically the full height of the tank. In practice, however, this cannot be accomplished. Besides, this process can only be used for separating 30 the coals into two products, so that the material sunk to the bottom must again be washed in order to avoid losses of valuable middlings.

Conklin has already drawn attention to the 35 fact that the rising currents in the washing tank and also the agitation of the suspension may be omitted if the sand is very finely divided and has a particle size of say 0.1 mm. It is said that in this manner a very stable suspension can be obtained and that the latter preserves during a long time 40 a uniform density throughout the tank. However, practically sufficient stability of the suspension requires such an extraordinary fineness of the sand as to render the process uneconomical. In practice it cannot be avoided that the 45 sand slowly settles, the consequence being that after some time the density of the suspension gradually increases in downward direction, and that a certain amount of middlings, i. e. coal of intermediate ash content such as bony coal, re- 50 mains suspended between the surface, from which the lower gravity product is skimmed and the bottom, from which the heavy refuse is to be discharged. Stated in other language, there may 55 gradually accumulate such a big amount of middlings in the intermediate layers of the sus-

pension, that the heavy material is prevented from sinking to the bottom and the further separation is seriously interfered with.

It has also been suggested to use more or less 5 colloidal substances for stabilizing the suspension, but these substances increase the viscosity of the fluid and impair the settling of the heavy material so as to make the separation very imperfect. Besides, also this process naturally allows of a 10 separation into two products only.

In accordance with my present invention, two or more layers with densities increasing in downward direction are allowed to form in the suspension in which, moreover, more or less horizontal currents are created for the purpose of carrying 15 the floating and the suspended products towards individual discharge means.

The stratification can be created by allowing the sand to settle, i. e. by turning to advantage a 20 phenomenon, which in known processes in the art works out as an inconvenience and which, therefore, has always necessitated special measures for 25 stabilizing the suspension.

A second method of obtaining the desired 30 stratification is, supplying the washing tank with suspensions of different densities.

It is pertinent here to remark that the word 35 "stratification" is not intended to convey the idea of distinct layers having different densities, since the density of the body of fluid in the tank increases very gradually in downward direction. This has the marked advantage that the middlings are distributed over the full depth and are not confined to one single sharply defined layer, so that there is no danger of undue accumulation 40 of middlings, as is the case with the Chance process.

For further explanation, reference is had to the diagrammatic drawings, in which Figs. 1 and 45 2 illustrate vertical longitudinal sections of two different washing tanks in accordance with my invention, while Fig. 3 illustrates an entire plant 50 installation including the form of apparatus shown in Fig. 2.

In Fig. 1, the tank 1 proper has vertical front 55 and rear walls, a substantially vertical left hand side wall and a slanting right hand side wall. Mounted on the left hand side of the tank there is a bucket elevator 2 having its delivery end 3 located vertically above an inclined dewatering screen 4. Opposite this screen there are some sprayers 5, and mounted below the same there is a boot 6.

The upper portion of the slanting right hand side wall of the tank 1 is double. The lower end 55

of the interspace 7 thus formed freely communicates with the tank, whereas the closed upper end thereof is connected with a discharge pipe 8 provided with a stop valve 9. A second pipe 10 serves for discharging the fluid flowing over the right hand side top edge 11 of the tank, whereas a third discharge pipe 12, having a stop valve 13, opens into the interspace 7 about in the middle thereof. A short distance above the overflow edge 10 11 ends an inclined dewatering screen 14 mounted on two boots 15 and 16, the upper one 15 of which discharges into the pipe 10.

A drag conveyor 17 provided with slotter or perforated scrapers and driven in anti-clockwise direction is mounted with its lower part substantially flush with the overflow edge 11 and so that its scrapers extend to a certain depth into the suspension, but at some distance from the edge 11 said part begins to move upwards at a certain angle. In parallel relation with this upwardly inclined part and at a small distance below the same there is provided a dewatering screen 18, the left hand side end of which is located somewhat below the level of the overflow edge 11. 25 The right hand side end of said screen meets the left hand side end of a downwardly inclined screen 19 mounted over the screen 14, and opposite the screen 19 there are provided some sprayers 20. 30 The right hand side wall of the tank 1 guides the lower part of a second drag conveyor 21, driven in clockwise direction and also provided with slotted or perforated scrapers. The upwardly moving part of this conveyor ends vertically 35 above the upper end of the screen 14. Intermediate the lower end of the conveyor 21 and the bottom of the tank 1 there is provided a partition 22 which, together with the inclined left hand side wall of the tank, defines a pocket 28 receiving the feed end of the bucket elevator 2.

Opening into the left hand side wall of the tank 1 there are three vertical, flat feed conduits 23, 24, 25, the width of which is substantially equal to that of the tank 1 and the discharge openings 45 of which are turned to the right. The opening of the conduit 23 is situated about at the level of the overflow edge 11, that of the conduit 24 about at the level of the opening of pipe 12, and that of conduit 25 about at the level of the top edge 50 of partition 22.

The described apparatus operates as follows: Presuming the tank 1 to be filled with the desired suspension of sand in water up to the overflow edge 11, the run-of-mine coal to be charged 55 into the tank as at A, i. e. on the left hand side of the tank, and the drag conveyors 17, 21 as well as the bucket elevator 2 to be suitably driven, the pure coal will float and be carried by the lower part of the conveyor 17 towards the screen 18 60 and raked over the same so as to be lifted out of the fluid, whereupon it slides down screen 19. This coal is washed by the water from the sprayers 20, and the adhering suspension together with the washing water is collected by the boots 65 15, 16.

The liquid drained from tank 1 through pipe 10 is replaced by fluid from the conduit 23. Since this fluid flows in horizontal direction near 70 the surface, it prevents the setting up of undesired vertical currents, which otherwise could be created by the operation of the conveyor 17.

The slate sinks to the bottom and accumulates in the pocket 28, from which it is removed by 75 the bucket elevator 2.

The middlings, for instance the bony coal, will sink below the surface of the suspension, but in view of the fact that the sand is not prevented from settling and that as a consequence the suspension has a density increasing in the direction from top to bottom, the middlings remain suspended at a greater or smaller depth. The fluid fed into the tank through the conduits 24 and 25 create currents from left to right intermediate the surface of the suspension and the bottom of the tank, whereby the suspended middlings are carried towards the drag conveyor 21 and discharged thereby. The said currents also cause pure coal and middlings, which may be carried along by the sinking slate, to be separated therefrom.

The pipes 8 and 12 also discharge certain amounts of fluid from the tank 1, said amounts being controlled by means of the stop valves 9 and 13 as conditions require.

The liquids discharged by the pipes 10, 8 and 12 are returned to the tank 1, if necessary after being purified (for instance by screens, froth flotation, etc.) and regenerated. According to requirements, the fluid from pipe 10 may be returned through conduit 23, that from pipe 12 through conduit 24, and that from pipe 8 through conduit 25. Alternatively, the liquid from 25 12 may be returned to 25 (or to both 25 and 24), that from 10 to 24 (or to both 23 and 24), and 30 stop valve 9 in pipe 8 kept closed. In this manner, upwardly inclined currents can be created in the tank, whereby the settling of the sand is counteracted.

The decrease of the density of the upper layer 35 and the increase of the density of the bottom layer may be compensated by the fluids discharged from the tank being wholly or partly mixed with one another before being returned to the tank. For instance, part of the suspension discharged by pipes 12 and/or 8 may be pumped to conduit 23, and part of the suspension drained by pipe 10 pumped to conduits 24 and/or 25.

If the aforesaid second method is used for obtaining the desired stratification, suspensions having increasing densities and stored in different reservoirs may be fed to the washing tank through the conduits 23, 24, 25 and discharged through the pipes 10, 12 and 8, respectively. 45 This is particularly useful when the sand is very finely divided, or when the suspension is excessively stabilized by impurities of the coals. If under these conditions one would rely exclusively upon the settling of the sand for the creation 55 of the desired stratification, the horizontal currents of liquid would have to be so feeble that undue accumulation of middlings in the tank would be likely to occur and the settling of the slate would thereby be impaired.

With the same object in view, the suspensions discharged as at 10, 12 and 8 may be collected in a common storing vessel in which the solid matter is allowed to settle to a certain extent, and from which the fluid is withdrawn at various levels, that is to say with different densities, to be fed to the conduits 23, 24, 25.

The washing water from the boots 6 and 16 may be purified in any appropriate manner, for instance by froth flotation, or by screening off 70 the coarser particles (say over 0.15 mm.). Alternatively, the separation of the sand from the finest slurry and slates can also be accomplished by gravity concentration. This possibility of removing the finest slurry and slates, which other- 75

wise would accumulate in the tank and thereby gradually increase the viscosity of the fluid so as to impair the closeness of the separation, is a highly advantageous feature of my invention.

5 In the Conklin process this removal is not possible, as the requirement of using a stable suspension necessitates the employment of exceptionally fine sand, so that the slurry cannot possibly be separated therefrom, at least not without substantial loss of sand.

10 The settling of the sand can also be controlled by bubbling air through the suspension, if desired in conjunction with upwardly inclined currents of liquid.

15 It will be understood that the middlings may still be graded in accordance with their specific gravities, by providing the tank with two or more conveyors 21 at different levels.

If necessary, the suspension may be stabilized 20 to a certain degree by means of colloidal substances. Preferably, high gravity material is employed as the solid constituent of the suspension, the nature of which depends upon the specific 25 weights of the desired middlings. If the range thereof is very wide, a relatively coarse suspension can suitably be used.

30 Instead of one single solid constituent of the suspension, a plurality of these constituents may be employed, the one being preferably very fine and the other somewhat coarser or heavier. This is of importance especially in those cases, where-in the coals to be dressed do not themselves contain a sufficient amount of stabilizing substances.

A suitable suspension consists of 50 parts by 35 weight of sand (consisting of equal parts of very finely ground fluorspar and ground magnetite) and 50 parts by weight of water.

The apparatus shown in Fig. 1 has proved to 40 operate satisfactorily under various conditions. Meanwhile, the fact that the substantially horizontal currents of liquid emanating from the inlet conduits 23, 24, 25 are bound to follow definite and invariable paths with any given setting of the apparatus may have the result that the 45 products kept in suspension intermediate the axes of said currents lag behind those suspended in said axes, or even remain stagnant. With a view to obtaining a more uniform transportation of said products towards the drag conveyors, Fig. 50 2 illustrates an improved apparatus, in which the openings through which fluid is fed to and discharged from the tank are adapted to be moved up and down. By these means each of said currents is enabled to sweep a zone of comparatively 55 great depth and stagnancy of fluid is thus positively avoided throughout the tank.

Like reference numerals indicate like parts in all figures.

The construction of the tank shown in Fig. 2 60 does not differ essentially from that of the tank illustrated in Fig. 1, so that it is not necessary to describe the same in detail.

As shown, the drag conveyor 17 may be passed either around a drum 26, or around a drum 27, 65 according to whether coarse coals or fine coals are to be treated.

The fluid supply pipes 23, 24 and 25 open into 70 chambers 29, 30 and 31, respectively, formed on the inner side of the left hand side wall of the tank 1. A slide valve 32, which is movable up and down in parallel relation with said side wall, forms the closure of these chambers and is provided with horizontal slots 33, 34, 35, through which said chambers communicate with the tank.

75 The chambers 29-31, the slide valve 32 and the

slots 33-35 all extend through substantially the full width of the tank.

In the drawings, the slide valve 32 is shown nearly in its extreme lower position, with the slots 33, 34 and 35 located near the bottoms of their 5 respective chambers 29, 30 and 31.

Similarly, the discharge pipes 8, 12 and 36 open into chambers 38, 39 and 40, respectively, the closure of which is formed by a second slide valve 41 having slots 42, 43 and 44, respectively. 10

During operation of this apparatus, the slide valves are slowly moved up and down, either manually or by suitable mechanism, the result being that each of the three substantially horizontal currents of fluid created at different depths 15 will sweep a zone defined by the extreme lower and upper positions of its inlet and outlet slots, so that the fluid is kept in movement throughout the depth of the tank and the suspended product is in its entirety transported towards the 20 drag conveyor 21.

Fig. 3 of the drawings diagrammatically illustrates a complete plant, comprising, in addition to a washing tank substantially as shown in Fig. 2, various auxiliaries for actuating the slide 25 valves, for returning and, if desired, mixing the various suspensions withdrawn from the tank, for creating rising currents of fluid in the tank, etc. Since in Fig. 3 like parts serve the same 30 purposes and are designated by the same reference numerals as in Fig. 2, it is not necessary to further describe the same. It will, however, be noted that the single flight conveyor 21 shown in Fig. 2 has been replaced in the plant of Fig. 3, by two conveyors 21a and 21b mounted at different 35 levels in the tank 1. Accordingly, the screen 14 as per Fig. 2 has been substituted in Fig. 3 by two superposed screens 14a, 14b.

ing into the bucket elevator 2 and provided with a valve 65, another valve 64 being mounted in pipe 48b intermediate said branch and the nozzle 53. By suitably setting valves 64 and 65, any desired proportion of the fluid supplied by pipe 48b may thus be discharged, through said elevator, near the bottom of tank 1 and create therein a rising current indicated by the arrow 66a.

10 Air may be bubbled through the suspension by means of a compressed air pipe 67 having a number of branches 69, each provided with a valve 68 and opening into the bottom of the tank.

15 The means for actuating the slide valves 32 and 41 comprise racks 56 and 59 secured to extended portions of said valves, respectively, and adapted to be driven by pinions 57 and 60, respectively. Pinion 57 is secured to a sprocket wheel 61 and pinion 60 is secured to a sprocket 20 wheel 62, a chain 58 being passed around said wheels, so that oscillatory movement imparted to wheel 61, or 62, will cause the slide valves 32. 41 to be moved up and down.

Having now fully described my invention, what 25 I claim is:

1. In a process for separating solid materials having different specific gravities by means of a suspension of sand in liquid contained in a tank in which the density of the suspension increases 30 from top to bottom, the steps which consist in feeding the materials to be separated into the bath at one side thereof, causing the heavier of said materials to settle in the bath, causing the lighter materials to float on the bath, causing 35 the materials with an intermediate specific gravity to remain suspended in the bath, withdrawing limited quantities of suspension per unit of time below the top level of the bath at the side opposite the feed side and introducing limited 40 quantities of the suspension per unit of time into said bath at the feed side thereof substantially at the withdrawal level so as to create a slow substantially horizontal current in the bath and cause the material with an intermediate specific 45 gravity to be carried towards the side opposite the feed side, separately removing from the bath floating material and suspended material, and simultaneously maintaining the portion of the bath out of the direct path of said current in a substantially quiescent condition.

50 2. In a process according to claim 1, the step of mixing the withdrawn suspension with suspension withdrawn from another level of the bath prior to returning the same into the tank.

55 3. In a process according to claim 1, the step of slowly changing the elevation of the slow substantially horizontal current in the bath.

4. In a process for separating solid materials 60 of varying specific gravities by means of a suspension of comminuted solids in a liquid bath contained in a tank in which the density of the suspension increases from top to bottom, the steps which consist in feeding the materials to be separated into the bath at one side thereof and permitting the same to respectively seek zone 65 levels corresponding to the specific gravities of the materials, introducing liquid suspension at the feed side of the bath below the surface thereof and simultaneously withdrawing a commensurate amount of liquid suspension from the bath at the opposite side thereof at a level corresponding to the introductory level, whereby to create a slow substantially horizontal current from side to side of the bath while simultaneously maintaining the portion of the bath out of the direct path

of said current in a substantially quiescent condition, to cause a portion of the materials having a certain specific gravity to be carried by said current from the feed side toward the discharge side of the bath and relative to another portion of said materials having a different specific gravity, and removing the material carried by said current from the bath at the discharge side thereof. 5

5. In a process for separating solid materials of varying specific gravities by means of a suspension of comminuted solids in a liquid bath contained in a tank in which the density of the suspension increases from top to bottom to form vertically spaced substantially horizontal zones of different specific gravities, the steps which consist in feeding the materials to be separated into the bath at one side thereof and permitting the same to respectively seek the zone levels corresponding to the specific gravities of the materials, separately introducing liquid suspension at 20 vertically spaced levels at the feed side of the bath and substantially at the upper surfaces of said spaced zones of suspension and simultaneously withdrawing commensurate amounts of liquid suspension from the bath at the opposite side thereof at vertically spaced levels corresponding to the introductory levels, whereby to create vertically spaced slow substantially horizontal currents from side to side of the bath while simultaneously maintaining the portion of the 25 bath out of the direct path of said currents in a substantially quiescent condition, to cause the materials of varying specific gravities to be carried by said currents from the feed side toward the discharge side of the bath, separately removing 30 said materials from the bath at the discharge side thereof independently of the withdrawal of the current-creating liquid, and changing the elevation of the slow substantially horizontal currents relative to the bath level during movement 35 of the materials through the bath so as to more thoroughly traverse the zones through which said currents are horizontally directed.

6. In a process for separating solid materials of varying specific gravities by means of a suspension of comminuted solids in a liquid bath 45 contained in a tank in which the density of the suspension increases from top to bottom to form vertically spaced substantially horizontal zones of different specific gravities, the steps which consist in feeding the materials to be separated into the bath at one side thereof and permitting the same to respectively seek the zone levels corresponding to the specific gravities of the materials, separately introducing liquid suspension at 50 vertically spaced levels at the feed side of the bath and substantially at the upper surfaces of said spaced zones of suspension and simultaneously withdrawing commensurate amounts of liquid suspension from the bath at the opposite 55 side thereof at vertically spaced levels corresponding to the introductory levels, whereby to create vertically spaced slow substantially horizontal currents from side to side of the bath while simultaneously maintaining the portion of the bath out of the direct path of said currents in a substantially quiescent condition, to cause the materials of varying specific gravities to be carried by said currents from the feed side toward the discharge side of the bath, and separately removing 60 said materials from the bath at the discharge side thereof independently of the withdrawal of the current-creating liquid suspension.

7. In a process for separating solid materials of varying specific gravities by means of a sus- 75

- pension of comminuted solids in a liquid bath contained in a tank in which the density of the suspension increases from top to bottom, the steps which consist in feeding the materials to be separated into the bath at one side thereof and permitting the same to respectively seek zone levels corresponding to the specific gravities of the materials, introducing liquid suspension at the feed side of the bath and simultaneously withdrawing 5
- 10 a commensurate amount of suspension from the bath at the opposite side thereof at a level corresponding to the introductory level, whereby to create a slow substantially horizontal current from side to side of the bath while simultaneously
- 15 maintaining the portion of the bath out of the direct path of said current in a substantially quiescent state, to cause a portion of the materials having a certain specific gravity to be carried by said current from the feed side toward 20 the discharge side of the bath and relative to another portion of said materials having a different specific gravity, removing the material carried by said current from the bath at the discharge side thereof, and changing the elevation 25 of the slow substantially horizontal current relative to the bath level during movement of the material through the bath so as to more thoroughly traverse the zone through which said current is horizontally directed.
- 30 8. Apparatus for separating solid materials having different specific gravities, comprising a tank for holding a body of suspension of comminuted solids in liquid, said tank having means associated therewith for removing material from the bottom 35 thereof and means for removing material from the level of the suspension in the tank; means for feeding the materials to be separated into said tank at one side thereof to permit said materials to respectively seek zone levels corresponding to varying specific gravities of the materials, independent means for introducing liquid suspension at the feed side of the tank and for withdrawing 5
- 10 liquid suspension therefrom at the opposite side thereof, said introducing and withdrawing means being respectively disposed at substantially the same level relative to the horizontal and below the level of the suspension in the tank, said liquid 15 suspension introducing and withdrawing means serving to create a slow moving substantially horizontal current in said tank for conveying materials to be separated thereacross, means at the discharge side of the said tank for removing separated material therefrom, and means for transferring liquid suspension withdrawn from said tank to said liquid introducing means.
9. Apparatus according to claim 8, including means for imparting up and down movements to the means for introducing liquid suspension into the tank and to the means for withdrawing said suspension from the tank. 20
10. Apparatus according to claim 8, including means for imparting up and down movements to the means for introducing liquid suspension into the tank and to the means for withdrawing said suspension from the tank, said movement imparting means including one or more individual chambers into which said suspension is respectively 25 introduced and withdrawn, open ported slide valves mounted for up and down movement and separating said chambers from the tank, and means for imparting synchronized up and down movements to said slide valves. 30
